REFRIGERATING APPARATUS

John Karmazin, Huntington, Ind., assignor to
 Karmazin Engineering Company, a corporation
 of Michigan

Application May 7, 1935, Serial No. 20,204

6 Claims. (Cl. 257—255)

This invention relates to refrigerating apparatus and more particularly to a combined condenser and receiver for use in refrigerating apparatus.

5 It is an object of the invention to provide a combined condenser and receiver which may be economically constructed and which is arranged to form a compact assembly by which the space required for the condenser and receiver ordinarily employed may be reduced.

10 It is also an object to provide a combined condenser and receiver wherein a receiver portion is mounted vertically alongside the condenser portion and is connected thereto in a manner to store condensed refrigerant to a level above the bottom of the heat exchange portion without flooding the heat exchange portion.

15 Further objects and advantages of the present invention will be apparent from the following description, reference being had to the accompanying drawing, wherein a preferred form of the present invention is clearly shown.

In the drawing:

20 Fig. 1 is a side view partly in cross section of a combined condenser and receiver embodying the present invention and showing diagrammatically the principal elements of a complete refrigerating system; and

25 Fig. 2 is a cross section on line 2—2 of Fig. 1. Referring now to Fig. 1, there is illustrated a refrigerating apparatus comprising a compressor 10 driven by a motor 12 for delivering compressed refrigerant through a conduit 14 to a combined condenser and receiver 16. Refrigerant liquefied in the condenser-receiver 16 is delivered through a conduit 18 to an evaporator 20. The evaporated refrigerant is withdrawn through a conduit 22 to the compressor 10 for recompression. Suitable automatic control means comprising a low pressure control switch 24 are provided for intermittently operating the motor 12 in accordance with the temperature conditions at the evaporator 20.

30 The condenser-receiver 16 comprises a heat exchange portion 26 formed of a plurality of horizontal tubes 28 and vertical fins 30. The tubes 28 are preferably formed integrally with the fins 30 by forming tapered tubular projections 32 in each fin and nesting the projections of the fins together in the manner illustrated. At one end of the heat exchange portion 26, an inlet header 34 is provided for connecting the right hand end of the tubes 28 in parallel circuit relation. At the other end of the heat ex-

change portion 26, a combined outlet header and receiver portion 36 is provided.

The portion 36 is formed from a cylindrical shell 38 having end closures 40 and 42. A suitable mounting bracket 44 is attached to the bottom end closure 40 by means of a combined drain fitting and attaching means 46. Near the bottom of the shell 38, an opening 48 is provided at one side thereof. The outlet header for the heat exchange portion 26 includes a portion of the wall of the shell 38 together with a trough-like sheet metal member 50 which is attached thereto in a manner to cover the opening 48. The trough-like member 50 is formed with a plurality of openings to which the projecting tubular portions 32 of the heat exchange portion 26 may be attached. Within the shell 38 and immediately above the opening 48, a partition 52 is provided having an opening 54 therein. An off-set tube 56 is mounted in the opening 54 and has an outlet 58 adjacent the top of the shell 38. Thus, there is formed within the shell 38 a chamber 60 for storing liquid refrigerant and a chamber 62 forming part of a passage between the heat exchange portion 26 and the interior of the chamber 60. The conduit 18 communicates with the chamber 60 through a connection 64 adjacent the bottom thereof.

35 In operation, compressed gaseous refrigerant enters the inlet header 34 and travels to the left through the tubes 28 where the latent heat is dissipated to the surrounding air by means of the fins 30. The refrigerant liquefies and passes through the inlet header 50, the opening 48, the chamber 62 and the tube 56 to the chamber 60 for storage. The stored liquid refrigerant is withdrawn through the conduit 18 as needed. It will be seen that the passage formed by the header 50, the opening 48, the chamber 62 and the tube 56 prevents the storage of liquid refrigerant within the heat exchange portion 26, inasmuch as the entrance to the tube 56 is below the lowermost tube of the heat exchange portion 26. Thus, there is provided a compact condenser and receiver construction which may be 40 economically constructed and which occupies less space than constructions heretofore utilized.

45 While the form of embodiment of the invention as herein disclosed constitutes a preferred form, it is to be understood that other forms 50 might be adopted, all coming within the scope of the claims which follow.

55 What is claimed is as follows:

1. A combined condenser and receiver for refrigerating apparatus comprising in combination

- a fin and tube heat exchange device having vertically spaced horizontal tubes, a vertical inlet header connecting said tubes at one end thereof, means forming a vertical outlet header and receiver connecting said tubes at the other end, and including a passage communicating between said tubes and the interior of said means and arranged to deliver condensed refrigerant to the interior thereof for collection therein to a level above the lowermost horizontal tube.
2. A combined condenser and receiver for refrigerating apparatus comprising a vertically extending heat exchange portion, a vertically extending receiver portion extending above the bottom of the heat exchange portion, and a conduit extending from the lower portion of the heat exchange portion to the upper part of the receiver portion, and serving as the sole connection between said portions.
3. A combined condenser and receiver for refrigerating apparatus comprising a vertically extending heat exchange portion, a vertically extending receiver portion extending above the bottom of the heat exchange portion, and a conduit extending from the lower portion of the heat exchange portion to the upper part of the receiver portion, and serving as the sole connection between said portions, said receiver portion comprising a cylindrical shell substantially coextensive vertically with the heat exchange portion.
4. A combined condenser and receiver for refrigerating apparatus comprising a vertically extending heat exchange portion, a vertically extending receiver portion extending above the

bottom of the heat exchange portion, and a conduit extending from the lower portion of the heat exchange portion to the upper part of the receiver portion and serving as the sole connection between said portions, said heat exchange portion comprising a plurality of horizontal tubes and vertical fins. 5

5. A combined condenser and receiver for refrigerating apparatus comprising a vertically extending heat exchange portion, a vertically extending receiver portion extending above the bottom of the heat exchange portion, and a conduit extending from the lower portion of the heat exchange portion to the upper part of the receiver portion and serving as the sole connection between said portions, said heat exchange portion comprising a plurality of horizontal tubes and vertical fins, and vertically extending headers at either end of said tubes. 10

6. A combined condenser and receiver for refrigerating apparatus comprising a vertically extending heat exchange portion, a vertically extending receiver portion extending above the bottom of the heat exchange portion, and a conduit extending from the lower portion of the heat exchange portion to the upper part of the receiver portion and serving as the sole connection between said portions, said heat exchange portion comprising a plurality of horizontal tubes and vertical fins, and vertically extending headers at either end of said tubes, one of said headers having a wall in common with the receiver portion. 15 25 30 35
